UNITED STATES PATENT OFFICE.

GEORGE H. BURGE, OF HUNTSVILLE, MISSOURI, ASSIGNEE OF ONE-HALF TO R. G. BURGE, OF HUNTSVILLE, MISSOURI.

RAIL-BOND.

1,113,875.

Specification of Letters Patent. Patented Oct. 13, 1914.

Application filed October 9, 1912. Serial No. 724,811.

To all whom it may concern:

Be it known that I, GEORGE H. BURGE, a citizen of the United States, residing at Huntsville, in the county of Randolph and State of Missouri, have invented new and useful Improvements in Rail-Bonds, of which the following is a specification.

This invention relates to rail bonds and especially to that type which are adapted for 10 electrically connecting the rails in mines and other similar places where they necessarily have to be moved at frequent intervals.

The object of this invention is to provide a simple and efficient device which may be 15 conveniently attached and detached to the rail base and which when applied will cause the sharp edge of the base to bind into the conductor or bonding wire.

Further objects of this invention will appear as the following specific description is read in connection with the accompanying drawing which forms a part of this application, and in which:—

Figure 1 is a side elevation showing the 25 device applied to a rail joint. Fig. 2 is a sectional view taken on the line 2—2 of Fig. 1. Fig. 3 is an enlarged sectional view taken through the clip removed from the rail.

Referring more particularly to the drawing 30 1 and 2 represent the separate rail ends which are connected in the usual manner by fish plates or like devices and which consist of a head 3, web 4 and base flange 5. The binding device comprises a substantially 35 V-shaped clip 6 having a conductor aperture 7 extending therethrough and a bolt aperture 8 through which the clamping bolt 9 is adapted to pass. This clamping bolt has a hook 10 formed at one end so as 40 to engage one of the base flanges of the rail and the opposite end is threaded to receive a clamp nut 11 which abuts the clip and forces it and the conductor toward the base flange. The clip is provided as shown with 45 a V-shaped aperture 12 which communicates with the channel 7 and permits the base flange to directly engage the conductor. (The said clip comprising a lower horizontally disposed leg portion or gripping surface 12' and the upper leg portion 13', the 50 opposed wall of the latter mentioned leg

member being inclined upwardly and outwardly as indicated at 14 whereby the same will snugly engage with the upper surface of the base flange 5.) Two of these bonding devices are necessary to connect the rails at a joint and each one is operated in a similar manner. After the conductor has been placed in the aperture 7 and the hook 10 arranged over the base flange the clip is 55 slipped onto the bolt and the nut 11 tightened so as to force the conductor into engagement with the sharp edge of the opposite base flange thereby causing said base flange to bite into the conductor and to secure a good operative connection.

What is claimed is:—

1. The herein described means for bonding two rails, including a conducting member arranged upon the edges of the base flanges of the rails, bolts having hooked ends engaging the operative longitudinal edges of the rails and having their shanks extending transversely of and beneath the base of the rails, a clip for each of the bolts, said 75 clips each including a base having an upper flat face upon which the rails rest, an overlying lip formed upon the outer end of the clip and having an inclined under face which rests upon the upper surface of the 80 base flange of the rail, an aperture at the juncture of its base and lip within which the conductor is received, and adjustable means upon the bolts for moving the clip toward the rails to compress the rails and 85 to wedge the lip and base portions of the clips against the rails.

2. The herein described means for bonding two rails including a conducting member arranged upon the edges of the base flanges of the rails, bolts having hooked ends engaging the opposite longitudinal edges of the rails and having their shanks extending transversely of and beneath the base of the rails, a yieldable clip for each of the bolts, 95 said clips each including a base having an upper flat face upon which the rails rest, a lip formed upon the outer end of the clip and having an inclined under face which rests upon the upper surface of the base flange of 100 the rail, said lip being disposed above and in superposed relation with the flat surfaces

of the base for its entire length, the base portion of the clip having an inclined undersurface through which the bolt passes, an aperture at the juncture of the base and 5 lip within which the conductor is received, and means upon the bolts for moving the clips toward the rails to compress the conductor against the rails and to spread the

lip and base portion of the clips against the rails.

In testimony whereof I affix my signature in presence of two witnesses.

GEORGE H. BURGE.
